UNITED STATES PATENT OFFICE

HENRY L. CROWLEY, OF WEST ORANGE, NEW JERSEY, ASSIGNOR TO HENRY L. CROWLEY & CO. INC., OF WEST ORANGE, NEW JERSEY, A CORPORATION OF NEW JERSEY

HEATER ARRANGEMENT FOR INDIRECTLY HEATED CATHODES

Application filed April 5, 1930. Serial No. 441,743.

This invention relates to heater arrangements for indirectly heated cathodes such as are employed in the socalled alternating current vacuum tubes employed in radio and 5 operated from the ordinary AC lighting systems.

The object of the invention is to provide a simple, efficient and inexpensive arrangement of the socalled twin hole insulator commonly employed in tube structures of this 10 nature with respect to the electron emissive element employed in connection therewith to reduce the amount of lapsed time between the time the vacuum tube is supplied with current 15 and the time the electron emissive element becomes sufficiently active.

Other objects of the invention will appear more fully hereinafter. The invention consists substantially in the construction, combination and relative arrangement of parts 20 all as will be more fully hereinafter set forth as shown in the accompanying drawing and finally pointed out in the appended claims.

Referring to the drawing: 25 Figure 1 is a view in perspective of an electron emissive and insulator element embodying my invention;

Fig. 2 is a longitudinal sectional view thereof;

Fig. 3 is a similar view of a slightly modified character.

Similar reference characters refer to similar parts throughout the several views of the drawing.

It is among the special purposes of my present invention to provide an arrangement of a twin hole insulator with respect to the electron emissive element employed in indirectly heated cathode tube structures in radio 35 receivers where current supply is ordinarily obtained from an alternating current source such as electric lighting means. It is well known that in tube structures of this type a considerable amount of time elapses between

45 the time the switch of the radio receiver is turned on and the time the tubes become active. This is due to the fact that the electron emissive element must be heated to a required degree before the tube is operative. The required heat for the electron emissive element

is secured from the incandescent filament of the tube which is usually of the hairpin type, the respective legs of which are, of necessity, positioned in the respective holes of a so-called twin hole insulator. It has been the 55 common practice to provide the electron emissive element, sometimes known as a shield, in the form of a cylinder suitably coated with the electron emissive material. Inside of this cylinder and usually in closed contact therewith is positioned the twin hole insulator through the two holes of which the filament extends. By means of this arrangement the filament when lighted must first heat the insulator and thereafter the heat by conduction 60 is imparted to the electron emissive element to render the same operative. The life and efficiency of a tube is largely dependent upon the surface area of the electron emissive element. Therefore, it is desirable to have the 65 same as large as the structural design of the tube will permit. It is, of course, obvious that the larger the insulator the longer time will be required to effect heat transfer from the filament to the electron emissive element. For 70 these reasons a mean size has usually been adopted in which, however, maximum surface area of electron emissive material is in no sense utilized notwithstanding its obvious 75 advantages.

It is among the special purposes of my invention therefore to provide a structural arrangement of the insulator and electron emissive element which will permit a maximum surface area of electron emissive material 80 and a minimum diameter of twin hole or other type of insulator thereby increasing the efficiency of the tube and reducing the inactive period of the tube after current is supplied thereto.

Referring to the drawing the reference numeral 1 designates the insulator which is shown as of the twin hole type and through which the holes 2 and 3 extend. The electron emissive shield, as is usual, surrounds the insulator but instead of being in close contact therewith as heretofore employed, it is made of any desired diameter, limited only by the dimensional design of the tube. Either one or both ends of the shield is bent, drawn or 95 100

otherwise formed inwardly so that the inner circumference thereof is in rigid supporting contact with the end of the insulator 1. The shield which is numbered 4 on the drawing has formed thereon or therein the electron-emissive material in the usual well known way. Obviously, by increasing the diameter of the shield 4 but retaining the diameter of the insulator 1 constant any desired surface 10 area of electron emissive material may be secured. This structure not only gives the insulator its necessary rigidity of support but in addition to effecting the heating of the shield 4 by radiation from the insulator to 15 the shield throughout its length intermediate its ends it also effects a heating of the shield by conduction because of the contact between the shield and the insulator at its respective ends. Thus heating by conduction 20 as well as by radiation is effected with the minimum amount of insulation necessary to be heated without limit other than the structural design of the tube as to the amount of electron emissive surface available.

25 As shown in Fig. 2 the shield 4 with its reduced ends may be formed in one piece or, if desired, the intermediate or body portion of the shield may be formed in one piece as shown in Fig. 3 and the end portions thereof, 30 designated 5 on the drawing, may be welded, braised or otherwise secured thereto.

Many modifications and changes in detail will readily occur to those skilled in the art without departing from the spirit and scope 35 of my invention. For example, I do not desire to be limited to any particular type or style of shield or electron emissive member, nor do I desire to be limited or restricted to any particular type, style or material of insulation, or whether it be of the twin hole 40 type or of some other type, but have now set forth the objects and nature of my invention and having shown and described structures embodying the principles thereof what I 45 claim as new and useful and of my own invention and desire to secure by Letters Patent is:

1. The combination with an emissive member in the form of a removable sleeve, an 50 insulator rod positioned within said sleeve, said sleeve being of reduced diameter at its ends and fitting closely to the said rod whereby said sleeve is held in spaced relation to said rod throughout the greater portion of its 55 length, and a longitudinal bore through said rod to receive a heater wire.

2. The combination with a sleeve-like electron emissive element, of a twin hole insulator 60 positioned therein, and means for supporting the ends of said twin hole insulator by contact with the ends of said element but out of contact throughout the remainder of the length thereof, comprising inwardly 65 tapered end portions attached to said sleeve-

like member and engaging the outer periphery of said insulator.

In testimony whereof I have hereunto set my hand on this 3rd day of April A. D., 1930.

HENRY L. CROWLEY.
